RESILIENT COASTING SLED

George O. Forseth, Minneapolis, Minn.

Application April 10, 1946, Serial No. 661,115

9 Claims. (Cl. 280—22)

1

This invention relates to new and useful improvements in sleds and more particularly to coasting sleds of the flexible runner type wherein flexing of the runners is utilized to secure a steering effect of the sled.

An important object of the present invention resides in the general construction of a sled comprising an upper substantially rectangular frame adapted to support a deck or seat, and a runner section comprising spaced runners, the forward ends of which have rearwardly extending horizontal portions having suitable universal joints connecting them to the forward end of the deck-supporting frame, and the rear ends of the runners being bent upwardly and forwardly to provide resilient arms having means for operatively connecting them to the deck-supporting frame at points spaced well forwardly of the rear end of said frame, whereby said forwardly extending arms cooperate to provide a resilient support for the deck-supporting frame.

A further object is to provide a sled comprising a rectangular seat or deck-supporting frame of tubular stock provided at its front end with forwardly extending portions, and each runner of said sled being formed of a single piece of resilient tubular stock, each having one end bent upwardly and rearwardly to provide the front ends of the runners, and the rearwardly extending portions of the front ends of said runners having means for pivotally connecting them to the forwardly extending portions of the deck-supporting frame, and the rear end portion of each of said runners being bent upwardly, forwardly and downwardly, to provide resilient arms having their free ends loosely connected to the intermediate portions of the runners, thereby to provide, in effect, semi-elliptic springs having their intermediate portions pivotally connected to the deck-supporting frame, whereby said spring arms cooperate to provide a resilient mounting for the deck, to cushion shocks and render the sled more comfortable to ride on.

A further object is to provide a sled having a deck-supporting frame constructed of steel tubing, and the runners of the sled also being constructed of steel tubing having sufficient resiliency to permit flexing of the runners for steering purposes, and each runner being provided at its rear end with a forwardly extending resilient arm having a movable connection with the deck-supporting frame at a location spaced well forwardly of the rear end of said frame, whereby the rear overhanging portion of the deck may

2

flex under a load to thereby cooperate with the resilient arms to absorb shocks.

A further object is to provide a coating sled wherein the deck-supporting frame and the runners are made of a light-gauge resilient steel tubing, and the rear ends of each runner have integrally formed therewith a forwardly extending resilient arm, which arms have their forward free ends movably connected to the deck-supporting frame, and complementary resilient arms each having one end secured to the intermediate portion of one of said runners and extending rearwardly with their free ends pivotally connected to the deck-supporting frame in proximity to the pivotal connections therewith of their respective forwardly extending resilient arms, and the free ends of each pair of resilient arms normally being spaced apart to permit free flexing of said arms under normal loads, but the spacing between each pair of said arms being such that when the arms of each pair of arms are subjected to an overload, the adjacent ends thereof will engage one another, thereby to prevent overflexing of the arms so that they are not likely to become damaged when occasionally subjected to an overload.

Other objects of the invention reside in the novel construction of the rear portions of the runners, whereby they provide a spring mounting for the deck portion of the sled; in the novel means provided for limiting flexing of the spring arms of the runners under abnormal loads, thereby to prevent overflexing thereof; in the provision of a sled comprising flexible runners and having means at its forward end for manually flexing the runners to steer the sled in its course; in the provision of a sled in which the deck-supporting frame and runners are made of metallic tubing, the deck-supporting frame being made as one unit, and the runner section being made as a second unit, and means being incorporated in the construction of said units whereby they may be quickly and inexpensively assembled to provide an exceedingly strong and durable sled which is light in weight, and in which the seat portion is resiliently supported on the runners to cushion shocks and the like when the sled is in use; and in the provision of a flexible runner sled of the steerable type which is neat and attractive in appearance, and which may be manufactured in quantity production at low cost.

Other objects of the invention will appear from the following description and the accompanying drawings and will be pointed out in the annexed claims.

In the accompanying drawings there has been disclosed a structure designed to carry out the various objects of the invention, but it is to be understood that the invention is not confined to the exact features shown, as various changes may be made within the scope of the claims which follow.

In the drawings:

Figure 1 is a plan view showing the means provided at the forward end of the sled for flexing the runners;

Figure 2 is a side view of the sled shown in Figure 1, showing the resilient mounting of the rear end portion of the deck-supporting frame;

Figure 3 is a front view of the sled shown in Figure 1;

Figure 4 is a cross-sectional view substantially on the line 4-4 of Figure 2;

Figure 5 is an enlarged detail view showing the resilient mounting of the rear end portion of the deck-supporting frame, and showing the resilient semi-elliptic spring arms in their normal positions;

Figure 6 is a view similar to Figure 5 showing the resilient arms as when flexed under a load, the dotted lines indicating the maximum flexing of the arms as when subjected to an overload;

Figure 7 is an enlarged detail sectional view on the line 7-7 of Figure 2;

Figure 8 is an enlarged detail sectional view substantially on the line 8-8 of Figure 1;

Figure 9 is a view showing the front end of a sled wherein the connecting means between the front ends of the two runners is somewhat differently constructed from the form shown in Figure 3;

Figure 10 is a view showing a modified construction of the connections between the front ends of the resilient arms and their respective runners;

Figure 11 is a sectional view on the line 11-11 of Figure 10;

Figure 12 is a view showing a sled wherein each runner is provided with two co-acting resilient arms for resiliently mounting the deck-supporting frame on the runners;

Figure 13 is a view similar to Figure 12 but showing the position of the resilient arms when the sled is under maximum load;

Figure 14 is an enlarged detail sectional view on the line 14-14 of Figure 12;

Figure 15 is a view showing another method of movably connecting the front ends of the resilient arms to the deck-supporting frame, wherein a suitable spring is interposed between the adjacent ends of each pair of arms for constantly urging the arm ends apart;

Figure 16 is a view corresponding to Figure 15, but showing the means for preventing overflexing of the arms, when the sled is subjected to an overload; and

Figure 17 is a detail sectional view on the line 17-17 of Figure 16.

In the selected embodiment of the invention herein disclosed, there is illustrated in Figures 1 and 2, a sled comprising a substantially rectangular deck-supporting frame, generally designated by the numeral 2, comprising side frame members 3 and 4, a rear arcuately formed cross member 5 and a front cross member 6 disposed in opposed relation to the rear cross member 5. The frame 2 is preferably formed with forwardly extending terminals 9 and 11, as shown in Figure 2, which extensions may be continuations of the tubular side frame members 3 and 4 of the frame 2.

Suitable cross members 12, 13 and 14 have their ends suitably secured to the side frame members 3 and 4, as by welding, and provide supports for a plurality of slats 15, which cooperate to provide the usual deck or seat 10 of the sled.

The side members 3 and 4 of the frame 2 may be made of a single piece of light steel tubing bent, as shown in Figure 1, and the front cross member 6 has its ends suitably welded to the side frame members 3 and 4, as will be understood. The cross members 12, 13 and 14 are preferably secured to the lower portions of the side frame members 3 and 4, as best shown in Figure 4, whereby when the deck slats 15 are secured thereto, they will be disposed slightly below the uppermost portions of the side frame members 3 and 4 and the cross members 5 and 6, as will be noted by reference to Figure 4. It will also be noted by reference to this figure that the seat portion of the sled is slightly concave, or downwardly curved transversely of the sled, and that the rearmost end of the deck 10 may also be slightly downwardly inclined, as indicated in Figures 5 and 6.

An important feature of the invention resides in the novel construction of the sled runners, whereby they provide the utmost in strength and rigidity and yet afford free flexing for guiding the sled in its course, and also whereby the deck-supporting frame 2 is resiliently supported on the runners.

As best shown in Figure 2, each runner 16 is formed from a single piece of steel tubing having one end bent upwardly and rearwardly to provide the front of the runner. Each runner is formed with a horizontal rearwardly extending portion 17. The portions 17 have their terminals pivotally secured to the forwardly extending portions 11 of the frame 2, preferably by means of ball-and-socket joints, such as indicated by the numeral 18 in Figure 8. The universal connections 18 are best shown in Figure 8, and each comprises a ball 19 received in a socket member 21 suitably secured in the end of one of the rearward extensions 17 of the front end of one of the runners. Each socket member is shown provided with a plug 23, which may readily be inserted into the ends of their respective extensions 17 and secured therein by suitable means, not shown. Each ball element 19 is similarly provided with a plug 24 suitably seated in the adjacent end of its respective forward extension 11 of the deck-supporting frame 2. By thus connecting the front ends of the runners to the frame 2, the lower ground engaging portions thereof may be freely flexed, as will subsequently be described.

Another important feature of the invention resides in the resilient mounting of the deck 10 on the runners. To thus resiliently support the deck 10 upon the runners, each runner is shown provided at its rear end with a forwardly extending arm 25 having its intermediate portion pivotally connected to its respective side member of the frame 2 by means of a pivot 26, received in aligned apertures provided in interlocking lugs 27 and 28 provided, respectively, on the frame members 3 and 4 and the resilient arms 25 of the runners. In Figures 2 and 6, the lugs 28 are shown bifurcated to provide increased strength.

Each spring arm 25 is upwardly arched, as best shown in Figure 6, and has its front end bent downwardly, to provide a short vertical section 29 provided with a forwardly extending

finger 31 received in a box-like bracket 32 secured to its respective runner 16 by such means as welding. The fingers 31 of the resilient arms 25 are guided in their vertical movements by the spaced side walls of the bracket 32, and the spacing between the top walls of the brackets 32 and their respective runners limits the vertical flexing movement of the free ends of said arms, as will be clearly understood by reference to Figures 5, 6 and 7.

In Figure 5 the resilient arm 25 is shown in its normal position, whereby the finger 31 is abuttingly engaged with the top wall of the bracket 32. When a load is imposed upon the deck 10 of the sled, the arms 25 are flexed downward, as indicated by the dotted lines in Figure 5, whereby said arms will absorb shocks and jolts imparted to the runners, when the sled is in use.

Should the arms 25 be subjected to an overload, the downwardly bent end portions 29 of the spring arms will engage their respective runners 16, as shown in Figure 6, and if the load is excessive, the arched portions of the arms may be depressed to the dotted line position, indicated by the numeral 33 in Figure 6. When the intermediate portions of the spring arms reach substantially the positions indicated at 33, the arms will elongate to close the gap 34 normally provided between the forward end portion 29 of each arm and its respective bracket 32, whereby further downward flexing of the spring arms 25 is prevented, thereby protecting the arms against overflexing when suddenly subjected to a severe shock or blow, as when the sled encounters a bump while speeding down an incline. Suitable tubular cross members 30 are interposed between the resilient spring arms 25, as indicated at 30 in dotted lines in Figures 1, 5 and 6, and full lines in Figures 1 and 9. These cross members have their ends welded to the arms 25, thereby to firmly brace the runners and strengthen them against lateral strains, as when rounding curves at high speed.

Figures 10 and 11 illustrate a slightly modified construction wherein the front end of each resilient arm 25 is shown provided with a forked member 36, which members are pivotally connected to upright lugs 35 provided on the runners 16. The forked members 36 and lugs 35 are apertured to receive coupling pins 38, which are preferably secured to the forked members 36 by such means as riveting over the ends thereof, as indicated at 39 and 41 in Figure 11.

The upright lugs 35 secured to the runners 16 are slotted, as indicated at 42 in Figure 10, to receive the coupling pins 38. The coupling pins 38 mounted in the coupling members 36 are so related to the slots 42 that when the resilient arms 25 are in their normal unloaded positions, as shown in Figure 5, the coupling pins are engaged with the right-hand ends of the slots 42, when viewed as shown in Figure 10. Thus, when the sled is subjected to a load and the resilient arms 25 are flexed, as shown, for example, in Figure 6, the arms 25 may elongate, and such elongation of the resilient arms is limited by the pivot pins 38 engaging the opposite ends of the slots, as will be understood. The length of the slots 42 is such that the pins 38 will engage the forward ends thereof before the resilient arms 25 can be flexed beyond their safe load-carrying positions.

In Figures 12 and 13, there is shown another construction, wherein each runner is provided with a pair of opposed resilient arms 43 and 44.

Each rear arm 43 is formed integrally with its complementary runner 16, and the rearwardly extending arms 44 are formed from tubular stock and have their forward ends suitably secured to the intermediate portion of the runners 16 by such means as welding, as indicated at 45 in Figure 12. The free ends of the resilient arms 43 and 44 are connected to the side members 3 and 4 of the upper deck-supporting frame 2 by suitable links 46 which have their lower ends pivotally connected to the arms and their upper ends to suitable lugs 47 secured to the side frame members 3 and 4 of the frame 2, as will be clearly understood by reference to Figures 12, 13 and 14.

The spacing between lower ends of each pair of the links 46 of the resilient arms 43 and 44 is such that they will contact each other before the resilient arms can be flexed beyond their safe load-carrying capacity, as shown in Figure 13. Suitable tie rods 39 are interposed between the corresponding resilient arms of the two runners, thereby to suitably brace the runners, whereby they may resist lateral strains imposed thereon when the sled is in use, and particularly when rounding curves.

Figures 15 and 16 disclose another modified construction wherein the resilient arms 43 and 44 of each such pair of arms are shown provided with ball-shaped terminals 48, received in tubular guides 49 secured to the side members 3 and 4 of the deck-supporting frame 2, by such means as welding, as indicated at 40 in Figure 17. Each guide 49 has its bottom and end walls suitably slotted, as shown, to receive the reduced necks 50 of the plugs 51, which secure the ball-like terminals 48 to their respective spring arms 43 and 44. The plugs 51 may be inserted into the ends of their respective tubular arms and welded therein.

A suitable spring 52 is provided in each guide 49, and have their ends seated against flanged plugs 53, which directly engage the ball-like terminals 48 of each pair of resilient arms 43 and 44. The inner ends 60 of the plugs 53 are normally spaced apart, as shown in Figure 15, when the sled 2 is unloaded or only partially loaded. When a normal load is imposed on the sled, the coil springs 52 between the ball-like terminals 48 of each pair of arms will partially compress, thereby cooperating with the arms 43 and 44 to resiliently support the load. Should an overload be imposed on the sled, the inner ends of the plugs 53 will engage one another, as shown in Figure 16, thereby preventing overflexing of the resilient arms and thus protecting them against damage as a result of overloads.

By reference to Figure 2, it will be noted that the pivotal connection between the deck-supporting frame 2 and the resilient arms of the runners is spaced well forwardly of the rear end of the frame 2, whereby the overhanging end of the deck may flex to some extent in addition to the flexing of the resilient arms of the runners. The spring mounting of the frame 2 on the runners thus provides a very easy and smooth riding sled, as all shocks and jolts are absorbed by the spring arms and the flexibility of the rear portion of the deck-supporting frame. The cross members 30 between the resilient arms of the runners securely tie together the spaced resilient arms of the two runners, whereby the runners are well-braced so that the runners are not likely to become distorted or collapse when the sled is rounding sharp curves at high speed. The cross members 30 are preferably constructed of the

same tubular material from which the runners are formed, so that they may flex to some degree when side strains are imposed upon the runners.

Means is also provided for steering the sled when coasting downhill and is shown comprising a suitable handle bar 54 provided with suitable hand grips 55, as best shown in Figures 1 and 3. The handle bar is secured to a strap-like member 56 having its rear end pivotally connected to the front cross bar 6 of the deck-supporting frame 2. The front end of the member 56 is pivotally connected to a cross frame member, generally designated by the numeral 57. The member 57 may be formed from sheet metal, and is preferably shaped as shown in Figure 3. Its end portions may be provided with elongated tubular guides 58 adapted to receive pivot bolts 59, the end portions of which are received in vertically spaced apertured lugs 61 and 62, the upper lugs 61 being shown secured to the upper rearward extensions 17 of the front ends of the runners, and the lower lugs 62 being secured to suitable gusset plates 63, fitted into and secured to the front ends of the runners, as best shown in Figure 2, thereby providing a very rugged construction which, at the same time, is very light in weight. The inclusion of the gusset plates 63 in the front ends of the runners greatly strengthens the runners, as will be understood.

To guide the sled, the handle bar may be swung from its normal full-line position, shown in Figure 1, to the dotted line position shown therein, whereby the runners 16 are flexed to the left to guide the sled in that general direction. The runners flex substantially the full length thereof, as indicated by the dotted lines in Figure 1, which is highly desirable. When the front ends of the runners are thus flexed to either side, the upper rearwardly extending horizontal portions 17 thereof pivot about the ball-and-socket joints 18, such joints permitting free flexing of the runners in either direction, whereby the sled may readily and conveniently be guided in its course without effort.

In Figure 9, there is shown a construction wherein a skeleton-like cross member, generally designated by the numeral 64, is provided in lieu of the cross member 57, shown in Figure 3. The cross member illustrated in Figure 9 is shown comprising an upper horizontal member 65 having its terminals pivotally connected to the inwardly directed lugs 61 provided on the runners 16, and to the intermediate portion of which the steering bar 56 is connected, as will be understood. Diagonal braces 66 have their inner upper ends secured to the upper horizontal member 65, as by welding, and their opposite ends are pivoted to the lugs 62 of the runners, thereby to provide a structural frame-like device having adequate strength to support the front ends of the runners.

The novel sled herein disclosed readily lends itself for manufacture in quantity production at small cost. In the manufacture thereof, the upper rectangular deck-supporting frame 2 may be formed as a unit, the side frame members 3 and 4 and the rear cross member 5 being made from a single piece of tubing, and the front cross member 6 having its end portions suitably welded to the side members 3 and 4 to provide a rigid frame structure.

As hereinbefore stated, each runner, including its spring arms 25 or 43, is formed from a single piece of resilient steel tubing, and the cross braces 30 have their ends welded to the spring arms,

whereby the two runners and spring arms may be assembled as a unit. The steering apparatus, including the handle bar 54 and cross frame member 57, may also be assembled as a unit, as will be understood.

Thus, when the three main parts of the sled have been assembled as three individual units, such units may readily and quickly be secured together to complete the formation of the sled by the provision of suitable assembling jigs and tools, well known in the art.

It will be apparent to those skilled in the art that I have accomplished at least the principal objects of my invention, and it will be also be apparent to those skilled in the art that the embodiments herein described may be variously changed and modified without departing from the spirit of the invention, and that the invention is capable of uses and has advantages not herein specifically described; hence it will be appreciated that the herein disclosed embodiments are illustrative only, and that my invention is not limited thereto.

What I claim is:

1. A sled comprising an upper rectangular deck-supporting frame, a pair of spaced tubular runners provided at their forward ends with rearwardly extending portions having their terminals connected to the front end of the deck-supporting frame by ball-and-socket joints, and each of said runners being provided at its rear portion with a pair of opposed resilient arms having their free ends pivotally connected to the deck-supporting frame, thereby to resiliently support the deck upon the runners.

2. A sled comprising an upper rectangular deck-supporting frame, a pair of spaced tubular runners provided at their forward ends with rearwardly extending portions having their terminals pivotally connected to the front end of the deck-supporting frame, each of said runners being provided at its rear portion with a pair of opposed resilient arms having their free ends pivotally connected to the deck-supporting frame, thereby to resiliently support the deck upon the runners, and means for limiting flexing of said resilient arms when subjected to an overload.

3. A sled comprising an upper rectangular deck-supporting frame of steel tubing, a pair of spaced tubular runners provided at their forward ends with rearwardly extending portions having their terminals movably connected to the front end of the deck-supporting frame, each of said runners being provided at its rear portion with a pair of opposed resilient arms, the free ends of each pair of said resilient arms being disposed in proximity to each other and having means for movably connecting them to the deck-supporting frame, and means operatively connected to the adjacently disposed free ends of each pair of said arms for limiting flexing movement thereof under a load.

4. A sled comprising an upper rectangular deck-supporting frame of steel tubing, a pair of spaced tubular runners having means at their forward end portions for pivotally connecting them to the front end of the deck-supporting frame, each of said runners being provided at its rear portion with a pair of opposed resilient arms having their free ends disposed adjacent to one another, tubular guides secured to the side members of the deck-supporting frame for operatively connecting the free ends of said resilient arms to said frame, and spring elements interposed between the adjacent ends of each pair of said arms

for constantly urging them apart and cooperating therewith to resiliently support a load carried on the sled.

5. A sled comprising an upper rectangular deck-supporting frame of steel tubing, a pair of spaced tubular runners having means at their forward end portions for pivotally connecting them to the front end of the deck-supporting frame, each of said runners being provided at its rear portion with a pair of opposed resilient arms having their free ends disposed adjacent to one another, tubular guides secured to the side members of the deck-supporting frame for operatively connecting the free ends of said resilient arms to said frame, spring elements interposed between the adjacent ends of each pair of said arms for constantly urging them apart and cooperating therewith to resiliently support a load carried on the sled, and means in each of said guides for limiting movement of the arm terminals mounted therein, towards one another, thereby to prevent overflexing of said arms when subjected to an overload.

6. A sled comprising an upper rectangular deck-supporting frame of tubular steel, a pair of spaced flexible tubular runners having means at their forward end portions for pivotally connecting them to the front end of the deck-supporting frame, each of said runners being provided at its rear portion with a pair of opposed resilient arms having their free ends disposed adjacent to one another, means movably connecting the adjacent ends of each pair of said arms to the deck-supporting frame, means for limiting flexing of said arms when subjected to an overload, and steering means at the front end of the sled whereby said runners may be flexed substantially the full length thereof, thereby to guide the sled in its traveling movement.

7. A sled comprising an upper rectangular deck-supporting frame of tubular steel, a pair of spaced flexible tubular runners, ball-and-socket joints for connecting the runners to the front end of the deck-supporting frame, each of said runners being provided at its rear portion with a forwardly directed integral resilient arm, a second resilient arm secured to the intermediate portion of each runner and having its free end rearwardly directed and disposed in proximity to the free end of its complementary forwardly directed arm, means movably connecting the free ends of each pair of said arms to the deck-supporting frame for limiting flexing of said arms when subjected to an overload, and steering means at the front end of the sled whereby said runners may be flexed substantially the full

length thereof, thereby to guide the sled in its traveling movement.

8. In a sled of the class described, a unitary rectangular metallic deck-supporting frame provided at opposite sides, intermediate the ends thereof, with runner attaching devices, a runner section comprising spaced runners provided with resilient arms having their free ends disposed in close proximity to the midportions of their respective runners, a steering device for flexing the forward ends of the runners to guide the sled, and coupling means secured to said resilient arms and engageable with the runner attaching devices on the deck-supporting frame, thereby to facilitate the operation of securing the arms to the deck-supporting frame.

9. In a sled of the class described, an elongated deck-supporting frame, a pair of spaced flexible metallic runners having rearwardly extending horizontal portions at their forward ends, means movably connecting said rearwardly extending runner portions to the forward end of the deck-supporting frame, the rear end portions of said runners having forwardly extending resilient arms, means pivotally connecting the forward ends of said resilient arms to the deck-supporting frame at points spaced well forwardly of the rear end of the deck-supporting frame, a deck supported within the deck-supporting frame, and a pair of auxiliary resilient arms having their forward ends fixedly secured to the intermediate portions of their respective runners and their rear free ends connected to the side rails of the deck-supporting frame adjacent to said forwardly extending rear runner arms, said auxiliary arms cooperating with the rear forwardly extending runner arms to resiliently support the deck.
